CLAIM

The ornamental design for a shoe as shown and described.

DESCRIPTION

FIG. 1 is a front perspective view of a shoe showing my new design;

FIG. 2 is a side view thereof;

FIG. 3 is an opposite side front perspective view thereof; and,

FIG. 4 is an opposite side view thereof.

The even-length broken lines within the shaded area represent stitching that forms no part of the claimed design. The uneven-length broken lines immediately adjacent to the bottom of the shaded areas define the bounds of the claimed design and form no part thereof. The uneven-length broken lines depicting the remainder of the shoe form no part of the claimed design.
